UNITED STATES PATENT OFFICE.

EDGAR P. WEBSTER, OF BRIDGEPORT, CONNECTICUT.

PENCIL-SHARPENING MACHINE.

1,040,069.

Specification of Letters Patent.

Patented Oct. 1, 1912.

Original application filed April 14, 1911, Serial No. 621,075. Divided and this application filed May 23, 1911.
Serial No. 629,040.

To all whom it may concern:

Be it known that I, EDGAR P. WEBSTER, a citizen of the United States, residing in the city of Bridgeport, county of Fairfield, State 5 of Connecticut, have invented certain new and useful Improvements in Pencil-Sharpening Machines; and I do declare the following to be a full, clear, and exact description of the invention, such as will enable 10 others skilled in the art to which it appertains to make and use the same.

My invention relates to certain new and useful improvements in pencil sharpening machines, and has for its object to provide 15 a machine of this description in which the pencil and cutter shall be revolved continuously in the same direction whereby at their points of contact during cutting said pencil and cutter will be traveling in reverse directions, while at the same time closer contact 20 between the pencil and cutter is established during the cutting of opposite portions of the pencil, so that a flat point is provided.

With these ends in view my invention consists in certain details of construction and 25 combination of parts such as will be herein-after more fully described and then particularly pointed out in the claims which conclude this description.

30 In the accompanying drawing Figure 1 is a sectional elevation of my improved machine—Fig. 2 a detail sectional elevation of the pencil clamping mechanism—Fig. 3 a section at the line α , α , of Fig. 1, and Fig. 4 35 a detail broken sectional elevation of a modification of my improvement.

Similar numerals of reference denote like parts in the several figures of the drawing.

In my pending application, Serial No. 40 621,075, filed April 14, 1911, I showed and described the same style of pencil sharpening machine as that herein set forth, but said application in its scope related solely to the cutting of a round point on the pencil 45 whereas the present application has reference solely to the formation of a flat point, and therefore I do not wish to be understood as claiming herein mechanism for forming such round point.

50 1 is any suitable casing to inclose the parts of my improvement, and 2 are horizontally disposed bottom plates secured to said casing. 3 is the frame of the machine preferably of cast metal, and secured to said plates 55 by means of screws 4. 5 is a horizontally

disposed annulus upon which said plates 2 normally rest, said annulus having secured thereto and depending therefrom suitable legs 6. The upper structure, composed of the casing 1 and plates 2, is hinged to the 60 annulus 5 at 7, and the inner upper surface of said annulus is counter-bored and a bottom cup 8 assembled therein so as to be readily removable therefrom in any ordinary 65 manner, said cup being formed with a laterally extending flange 9 which fits within said counter-bored portion so as to be flush with the upper surface of said annulus.

Journaled within the frame 3 in angular disposition is a cutter roll 10 which carries 70 a pinion 11 at its upper extremity, and located within a vertical opening 12 in the frame 3 is a pencil bushing 13 which is capable of vertical movements within said opening, within prescribed limits, as will be hereinafter more fully described. This bushing is formed with a downwardly tapering opening 14 extending from top to bottom, and said bushing is cut away at one side so as to admit the cutter roll 10 in juxtaposition 75 within said opening, so that it will be clearly understood that a pencil introduced down through this opening 14 would be within the field of operation of the cutter roll.

15 is a gage pin passed upwardly and 80 loosely through a thimble 16 held absolutely stationary between one of the plates 2 and the frame 3, the upper end of said pin having secured thereto a head 17 in proximity to the lower end of the bushing 13, while the 85 lower extremity of said pin is enlarged as seen at 18 and is provided with an enlarged or counter-bored portion 19 which leads within the interior of the upper portion of said pin. Around the upper portion of the 90 pin 15 and confined between the thimble 16 and head 17 is a coil spring 20 whose function is to normally elevate said pin. The lower edge of the thimble 16 has formed 95 therein notches 21, 22, the latter of which is deeper than the former, and around the pin 15 and immediately backed by the upper edge of the enlarged part 18 is a collar 23 that is secured to said pin as to rotation and 100 is provided with a tooth 24 extending upwardly therefrom and adapted to coöperate with the notches 21, 22, in the manner presently to be explained. Immediately beneath this collar 23 and engaging a threaded 105 part of the enlarged portion 18 is a nut 25, 110

and extending loosely through the smaller opening in the pin 15 is a screw bolt 26 whose upper extremity 27 is threaded and driven within the pencil bushing 13, the 5 lower end of this bolt being provided with a head 28 which is contained within the counter-bore 19. In assembling the machine this screw bolt 26 with its head against the upper wall of the counter bored portion 19 is 10 turned or driven until the bushing 13 is drawn downwardly to a plane where the cutter roll will be effective in operating against a pencil contained within said bushing, and this adjustment of the latter will 15 be readily understood when it is borne in mind that the screw bolt itself cannot advance because its head is in abutment against the inner wall of the counter-bored portion 19.

By turning or driving the nut 25 on the 20 enlarged portion 18 of the pin the latter will be drawn downwardly against the resiliency of the spring 20 thereby causing the head 17 to draw away from the bushing 13, and this adjustment is made in the assembling of the 25 machine in order to fix the normal distance between said bushing and head, since, as will be hereinafter explained, the point of the pencil rests upon this head, and the greater the distance between the latter and 30 said bushing the longer and sharper will the pencil point be fashioned by the cutter roll. This adjustment of the normal position of the head 17 with respect to the bushing 13 may be effected while the tooth 24 is within 35 either the shallow notch 21 or deep notch 22, and, if said adjustment is made while said tooth is within the deep notch 22 this will be effected for the shortest or bluntest point on the pencil whereas if said tooth is 40 within the shallow notch 21 such adjustment will be for the longest or sharpest point. If this adjustment has been made while the tooth 24 is within the deeper notch 22, the operator, in the event that he desires a long 45 point, merely grasps the part 18 and turns the pin until the tooth 24 has ridden into the shallow notch 21, thereby forcing the pin downwardly against the resiliency of the spring 20, and, as above described, with- 50 drawing the head 17 at a greater distance from the bushing 13. These adjustments, by means of the nut 25 and screw bolt 26, are merely factory expedients and are utilized solely for the purpose of properly fixing normal 55 conditions of the parts, since, in the sharpening of pencils, it is merely desired to obtain a short or blunt point and a long or sharp point, and these results are obtained by merely turning the pin bodily so as to cause the tooth 24 to coöperate with the notches 22 and 21.

In order to preserve the proper elevated position of the bushing 13 I employ a coil spring 29 which is housed within the counter-bore 19 and is confined by means of a

screw 30 driven within the end of the latter, and after this bushing has once been sufficiently depressed so as to be in the proper position for coöperating with the cutter roll 10 this position of said bushing is maintained by means of a stop 31 driven into the frame 3 immediately above the upper edge of the bushing. But, as a matter of fact, I prefer to adjust the gage pin with respect to the bushing when the tooth 24 is within the shallow notch 21 and this adjustment is of course made for the longest and sharpest point, and when the pin is turned to throw the tooth into the deeper notch 22 to elevate the pin, this will cause the inner wall of the counter-bore 19 to draw away from the head 28 so that there will be a space 32 between said wall and head, whereby when the tooth is shifted into the shallow notch the pin will be depressed without affecting the bolt 26 or 85 the bushing 13.

The cutter and the pencil are rotated simultaneously and continuously so as to travel at their points of contact in reverse directions by means of the following instrumentalities which I will now describe. Journaled within the frame 3 is a crank shaft 33 to whose outer extremity beyond the casing is fixed a crank 34, and carried by this shaft is a bevel gear 35 which meshes 95 with a comparatively large annular shaped bevel gear 36. 37 is an annulus resting upon the gear 36, and 38 is a hollow hub upon said annulus, and said gear, annulus, and hub are firmly secured together by 100 means of screws 39, so that it will be clear that these three parts will all rotate in harmony. The inner periphery of the annulus 37 has spur teeth 40 which mesh with the pinion 11, and the hub 38 at its upper end 105 is journaled around a reduced portion 41 of the frame, which portion is in the form of a vertically disposed socket and is exteriorly threaded at its upper end. Owing to the fact that the hub is journaled around a reduced portion of this part of the frame, said hub will be supported by the frame itself and will maintain the gear 36 and annulus 37 in proper horizontal position so that they will properly mesh with the gear 35 and pinion 11, and this hub is capable of free revolution around this reduced portion. 42 is a leather or other washer encircling the reduced portion of the frame and resting upon the top of the hub 38 and confined by means of a nut 43 driven on the threaded portion of said frame against said washer sufficiently tight to keep the hub from jumping upwardly during operation but not so tight as to interfere with the free rotation of 115 said hub. The upwardly projecting portion of this hub is exteriorly threaded, and an interiorly threaded cap 44 is secured thereto so as to revolve therewith. Contained within the socket portion of the reduced up- 120 125 130

wardly extending portion of the frame 41 is a loose sleeve 45 capable of free vertical and rotary movements within said socket and having its lower extremity extending inwardly and beveled as shown at 46, and 47 is a thimble whose lower portion is enlarged and fits loosely within the sleeve 45 so as to be capable of independent vertical and rotary movements therein, the upper end of which 5 is provided with a laterally extending finger lug 48 and a peripheral beveled tooth 49 which latter is adapted to engage with a beveled notch 50 formed within the upper edge of a ring 51 that loosely encircles the upper portion of the thimble 47 and is rigidly secured to the inner upper wall of the sleeve 45, said ring being likewise provided with a finger lug 52. A coil spring 53 encircles the reduced portion of the thimble 47 and is confined between the enlarged portion thereof and the lower edge of the ring 51, so that it will be clear that when the operator grasps these lugs 48, 52, and exerts sufficient force, the beveled tooth 49 10 will ride upwardly along the beveled wall of the notch 50 thereby slightly rotating the thimble 47 and elevating the same against the resiliency of the spring 53. Secured within the inner wall of the lower 15 part of the enlarged portion of the thimble 47 is a ring 54, and this portion of the thimble is cut away at intervals to form a suitable number of recesses 55, and loosely swung on this ring and contained freely 20 within these recesses are the pencil clamping jaws 56 that are preferably roughened on their exterior surfaces and of a general ovoidal shape, these jaws being loosely fitted around the ring near their upper portions. 25 a is a vertical slot in the outer surface of sleeve 45, and within this slot extends the inner upper edge of cap 44, so that it will be evident that said cap and sleeve will revolve in harmony. When the thimble 47 is 30 elevated in the manner above described these jaws will swing to a vertical plane as shown at Fig. 2, but when the operator releases the finger lugs 48, 52, the spring 53 will act to force the thimble downwardly 35 thereby forcing the lower ends of these jaws against the beveled surfaces 46, and this will throw the jaws inwardly toward each other. 40

In operating my improvement the sleeve 46 is elevated and the lugs 48, 52, are then 45 compressed in the manner above described and the pencil dropped through the thimble 47 so that its lower end will rest by gravity within the pencil bushing 13; the lugs are then released thereby causing the thimble to 50 be forced downwardly so that the jaws will firmly grip the pencil, and the sleeve 45 will remain elevated so that in addition to the weight of the pencil, there will be the weight 55 of the sleeve, the thimble and the parts connected therewith, to constantly force the

pencil downwardly by gravity and thus keep the lower end of said pencil always in proper relation with respect to the cutter.

It is necessary to provide some means for preventing the rotation of the pencil bushing 13, and therefore I utilize an ordinary device for this purpose such as a screw 57 driven through the frame and having a reduced tip which extends within an elongated slot 58 in the side of said bushing, and I furthermore provide any ordinary handle 59 at the end of the crank arm 34 in order to actuate the latter.

Referring to Fig. 1 of the drawing, 60 is an opening eccentrically located lengthwise 80 in the crank shaft 33 throughout the length of the latter, and 61 is a plunger within said opening and capable of free movements therein and having extending from its forward end a stud 62 immediately opposite a 85 suitably shaped recess 63 in the pencil bushing 13. 64 is a rod connected to said plunger, and to the outer end of said rod beyond the crank 34 is secured any suitable knob 65. 66 is a plug which is driven within the outer 90 end of the opening 60 and through which the rod 64 loosely extends, and 67 is a coil spring surrounding said rod and confined between the plunger 61 and plug 66, said spring acting to normally project the stud 95 62 within the recess 63.

In cutting a round point on a pencil in the manner described in my said application the rod 64 is retracted and kept in this position by the abutment of a pin 68 extending 100 from the hub of the knob 65 against the outer end of the shaft 33 as shown at Fig. 1, but by turning this knob so that said pin will come opposite to a notch 69 in the edge of said shaft the spring 67 will then 105 force the plunger 61 inwardly and thereby cause the stud 62 to enter the recess 63. Now when this stud 62 is within the recess 63, the revolution of the crank 34 will force 110 said stud downwardly against the lower wall of said recess and will thereby momentarily depress the bushing 13 as well as the gage pin 15, the spring 29 being more powerful than the spring 20. The shape of 115 the recess 63 is such that there is more or less lost motion while the stud 62 is operating within said recess, and therefore the depression of the bushing 13 and gage pin 15 by the operation of the crank 34 is such that it would occur only throughout about 120 one-sixth of a complete revolution of said crank, although this proportion might be altered to a greater or lesser degree as the occasion might demand. The proportion 125 between the gears 35 and 36 is such that a complete revolution of the former will effect only a half revolution of the latter, and therefore this depression of the bushing 13 and pin 15 will occur twice during a complete revolution of the gear 36, and since the pen- 130

cil is revolved in harmony with the gear 36 it follows that the cutting at the point of the pencil will be deeper on opposite sides of said point during a complete revolution of 5 the pencil while the cutting of the rest of the point will be effected as in the instance of a round point. Therefore it will be clear that by throwing the point into closer engagement with the cutter at predetermined 10 times so that opposite portions of said point will be cut deeper than the rest of the point a flat point may be obtained and this is something that has never before been done. 15 Of course it will be clearly understood 15 that the closer the cutting relation between the pencil and the cutter the deeper will be the cut effected, and therefore the same result can be obtained by adjusting the cutter itself at predetermined times nearer to the 20 pencil, and accordingly I have illustrated at Fig. 4 a modification of my improvement in this respect which I will now describe. 70 is an L-shaped lever whose horizontal member is supported on one of the bottom plates 25 2 immediately below the frame 3 while the upright member terminates in a beveled lug 71 adapted to be engaged by a beveled lug 72 carried by the gear 35 near its periphery. This L-shaped lever is capable of a free 30 shifting movement toward and away from the casing 1, and when the lug 72 engages the lug 71 it will force said lever toward said casing, a coil spring 73 having its extremities secured respectively to said lever 35 and to a pin 74 rising from the plate 2 serving to normally retract said lever. The lower journal of the cutter roll 10 is carried by the horizontal member of this lever 70 and extends through an enlarged opening 75 in the frame 3, so that it will be clear that as the crank 34 is revolved the cutter roll 10 will be thrown inwardly toward the pencil bushing whenever the lug 72 engages the lug 71, and this engagement of these lugs 40 and the consequent inward throw of the cutter roll occurs throughout only about one-sixth of the revolution of the crank 34, the pencil being rotated only half a complete revolution while the gear 35 is completing 45 a whole revolution, and therefore the same results as to the formation of a flat point will be obtained as in the instance above 50

described with respect to Fig. 1. I therefore do not wish to be limited to either the adjustment of the pencil bushing toward the 55 cutter or the adjustment of the latter toward the pencil bushing, since the same results, so far as the formation of a flat point is concerned, are obtained in both instances, my invention residing in the broad idea of 60 the formation of a flat point by the simultaneous and continuous rotation of the pencil clamping devices and cutter and the bringing of said devices and cutter into closer relation at predetermined times. 65

Having thus described my invention what I claim as new and desire to secure by Letters Patent is:—

1. In a pencil sharpening machine, the combination of a rotary cutter, a pencil receiving bushing adjacent said cutter, means for moving one of these elements toward the other at certain stated periods, and a pencil clamp freely movable vertically whereby when elevated a pencil clamped therein will 75 rest by gravity within said bushing.

2. In a pencil sharpening machine, the combination of a rotary cutter, a pencil receiving bushing adjacent said cutter, means for moving one of these elements toward the other at certain stated periods, and a rotary pencil clamp freely movable vertically whereby when elevated a pencil clamped therein will rest by gravity within said bushing. 80

3. In a pencil sharpening machine, the combination of a rotary cutter, a pencil receiving bushing adjacent said cutter, means for moving one of these elements toward the other at certain stated periods, a rotary pencil clamp freely movable vertically whereby when elevated a pencil clamped therein will rest by gravity within said bushing, and means for causing said pencil and cutter to simultaneously and continuously travel in reverse directions at their 90 point of contact. 95

In testimony whereof I affix my signature in presence of two witnesses.
